HYDRAULIC DRIVE

Emery F. Comstock, Cincinnati, Ohio, assignor of
one-half to Walter V. Hallerman, Cincinnati,
Ohio

Application February 10, 1944, Serial No. 521,834

3 Claims. (Cl. 74—189.5)

1

My invention relates to improvements in hydraulic drives for use more particularly, although not necessarily, between the engine and drive shaft of an automobile.

The principal object of my invention is to provide a simply constructed, hydraulic drive of the fluid clutch type adapted for easy control to either reverse an automobile, throw the same into "neutral," or automatically operate the same at variable speeds, all without the use of sliding gears.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of my improved hydraulic drive, in its preferred embodiment,

Figure 2 is a view in top plan,

Figure 3 is a view in vertical longitudinal section taken on the line 3—3 of Figure 2, and drawn to an enlarged scale,

Figure 4 is a view in rear end elevation,

Figure 5 is a view in vertical transverse section taken on the line 5—5 of Figure 3,

Figure 6 is a similar view taken on the line 6—6 of Figure 3,

Figure 7 is another similar view taken on the line 7—7 of Figure 3,

Figure 8 is still another similar view taken on the line 8—8 of Figure 3, and

Figure 9 is a view in side elevation of the rotor and driven shaft detached.

Referring now to the drawings by numerals, I designate the casing of my improved hydraulic drive and which has the form, preferably, of a cylindrical shell 2 provided with a pair of front and rear end heads 3, 4 bolted, as at 5, to the ends of the shell. A reduced diameter, cylindrical housing 6 extends from the front head 3 concentrically thereof, and is bolted thereto, as at 7, and provided with a circular front head 8 closing the same and forming a radial outstanding flange 9 provided with bolt holes 10 for receiving bolts 11 by means of which said flange may be fixed to the crankcase 12 of an automobile engine to align the housing 6 and casing 1 with the crank shaft, not shown, of said engine. The casing 1 forms an oil container and the housing 6 forms, together with the front head 3, a chamber 17 for a purpose presently seen. A filler plug 13 is provided in the top of the casing 1 and an inspection aperture

2

14 closed by a detachable cover plate 15 and gasket 16. The rear head 4 is provided with a reduced axial housing 18 for gearing to be described.

A drive shaft 19 extends axially through the housing 6 and into the casing 1 to substantially the housing 18, and at its rear end is telescopically and rotatably fitted into the hollow front end of a driven shaft 20 extending through the housing 18 into the casing 1 for a short distance and provided in said casing with a radial, circular end flange 21. The drive shaft 19 is designed to be connected, in any suitable manner, to the engine crank shaft, not shown, and the driven shaft 20 for suitable connection to the drive shaft of the automobile. A suitable packing gland 22 for the drive shaft 19 is provided on the head 8, and a ball bearing assembly 23 supports said shaft 19 adjacent the head 3. The rear end of the drive shaft 19 is mounted in a roller bearing 24 in the driven shaft 20. A ball bearing unit 25 for the driven shaft 20 is provided in the gear housing 18. The ball bearing assembly 23 is contained in a hub bushing 23a for the head 3 bolted to said head 3 as at 23b and extending into the shell 2. An oil sealing ring assembly 23c bolted to said hub bushing 23a, as at 23d, closes the outer end of said bushing.

In the casing 1 is a cylindrical, cage-like rotor 26 extending substantially from end to end of the casing and including disc-like front and rear ends 27, 28 adapted to rotate concentrically about the drive shaft 19, and a foraminous drum 29 suitably secured on said ends. The ends 27, 28 of said rotor are suitably spaced from the heads 3, 4 for a purpose presently seen. The front end 27 of said rotor 26 is rotatably mounted on said hub bushing 23a by an anti-friction bearing assembly 30. The rear end 28 of said rotor 26 is provided with an axial sleeve 31 extending into the drum 29 and mounted, through an anti-friction bearing 32, on said drive shaft 19. The rear end 28 of said rotor 26 is fixed to the flange 21 of the driven shaft as by the bolts 33.

A forward driving runner 34 of the usual dished type, with radial blades 35, such as shown in Figure 6, is loosely mounted by means of a sleeve-like hub 36 on the sleeve 31 of the rear end of the rotor 26 within the latter and for sliding movement on said sleeve or hub 36 toward and from said end 28 of the rotor 26. A yielding driving connection between said runner 34 and said rear end 28 of the rotor 26 is established by means of a circular, radial flange 37 on said hub 36 opposed to said end 28, studs 38 on the flange 37 extending rearwardly through apertures 39 in said end 28 and

having nuts 40 on the outer ends thereof, and coil springs 41 on said studs 38 interposed between said flange 37 and said rear end 28 of the rotor. The studs 38 are preferably arranged in a circular series. The forward driving runner 34 has its open side facing forwardly, and the bladed section thereof is bolted, as at 42, to the flange 37. The purpose of the described yielding connection will presently appear.

A reverse driving runner 43, similar to runner 34, but having the open side thereof facing rearwardly, is mounted on the drive shaft 19, contiguous the front end 27 of the rotor 26 and within the latter, by means of a sleeve-like hub 44, and an anti-friction bearing assembly 45 in said hub and surrounding said shaft 19. The reverse driving runner 43 is freely rotatable about the drive shaft 19. The mounting of said runner 43 on the drive shaft is such that the rotor is confined against lateral movement on said drive shaft as by a collar 46.

Reverse driving gearing is interposed between the reverse driving runner 43 and the rotor 26 as follows: An internal ring gear 47 is formed on the front end 27 of the rotor 26. A relatively smaller external ring gear 48 forms part of the hub 44 of the reverse driving runner 43 and to which the bladed part of said runner is bolted, as at 49. Reversing gear pinions 50 are interposed between said ring gears 47, 48. The reversing gear pinions 50 are rotatably mounted on studs 51 on a spider 50a keyed on the hub bushing 23a as at 50b, and secured thereon by a threaded collar 50c having set screws therein as at 50d. A sealing ring 50e closes the rear end of the hub bushing 23a.

A duplex impeller 52 is provided on the drive shaft 19 intermediate the forward driving runner 34 and the reverse driving runner 43 for shifting in opposite directions from a central intermediate position on said shaft into cooperating relation to either the runner 34 or the runner 43.

The impeller 52 comprises a pair of front and rear dished sections 53, 54, similar to the runners 34, 43, but oppositely facing and riveted, as at 55, to a central radial flange 56 of a sleeve-like hub 57 splined, as at 58, on the drive shaft 19 and also keyed to said shaft by means of a diametrical, internal key 59 extending through a longitudinal slot 60 in said shaft 19.

Impeller shifting means are provided comprising the following devices:

A circumferentially grooved collar 61 is slidably mounted on the drive shaft 19 in the chamber 17 for lateral shifting from an intermediate position rearwardly into a forward drive-selecting position, or forwardly into a reverse drive-selecting position. The usual yoke 62 with studs 63 engaging the groove of said collar 61 is provided for shifting the collar and is slidably mounted on a fixed guide 64 in the chamber 17. A yoke-shifting lever 65 is pivoted, as at 66, to said yoke 62 to extend laterally out of the housing 6 by way of a longitudinal slot 67 and to be engaged with rear, front and intermediate edge notches 68, 69, 70, respectively, of said slot to establish the forward and reverse drive-selecting positions of said collar and also its intermediate position. The collar 61 is operatively connected to the key 59 of the impeller hub 57 to shift the impeller and by means of a diametrical pin 71 on the collar 61 extending through a longitudinal slot 72 in the drive shaft 19, and an endwise movable rod 73 suitably connected to said pin and to said key 59, the rod being endwise movable in a bore 74 in the drive shaft 19

which is hollow in part to provide a bore of the proper extent.

As best shown in Figure 3, the driven shaft 20 is provided, in the housing 18, with a worm gear 75 thereon meshing with a worm 76 in said housing having one end extended out of the housing for connection in the usual manner to the speedometer shaft, not shown.

Referring now to the operation of the invention, 10 with the collar 61 shifted opposite the rear notch 69, and the lever 65 engaged with notch 68, as shown in Figure 1, the impeller 52 is shifted rearwardly on the drive shaft 19 into forward driving position to set the rear section 54 thereof into driving relation to the forward driving runner 34 with the necessary clearance so that under operation of the drive shaft 19 a fluid clutch will be established between said section and runner to transmit the drive from the drive shaft 19 directly to the driven shaft 20 in the same direction through the studs 38, the rear end head 28 of the rotor 26 and the flange 21 of said driven shaft 20. The forward driving position of the impeller 52 is established initially by the rear end of the hub 57 abutting the hub 36, and in this position of the parts, substantially no slippage occurs after high speed is attained under normal load on the driven shaft 20. However, under increase in load on said driven shaft 20, above normal, the described yielding connection, to wit, the studs 38 and springs 41 between the runner 34 and rotor 26 permit the runner 34 to move away from the impeller section 54 in degree proportionate to the increase in the load on the shaft 20 above normal to thereby permit slippage between the section 54 and the forward driving runner 34 so that 25 clutching conditions are obtained corresponding to second and low speeds in the usual automobile transmission, or to intermediate speeds, it being understood that the springs 41 are appropriately constructed.

When the collar 61 is in reverse drive setting opposite the notch 69 and the lever 65 is engaged in said notch, the impeller 52 is shifted forwardly to position the front section 53 thereof into cooperative relation with the reverse driving runner 43. This position of the impeller 52 is established by engagement of the front end of the hub 57 with the hub 44 of the reverse driving runner 43. Under the clutching relation established in this position of the parts, although the impeller 52 is rotating in the same direction as before, the driven shaft 20 is reversed relative to the drive shaft 19, the drive being transmitted from the drive shaft 19 through the front section 53 of the impeller 52, the reverse driving runner 43, the before-described gearing, reversing the direction of rotation of the rotor 26 relative to that of said runner 43 and thus reversing the driven shaft 20.

When the collar 61 is shifted opposite the notch 70, and the lever 65 engaged with said notch, the described impeller is shifted into an intermediate position between the forward and reverse driving runners 34, 43, such that no fluid clutching action can obtain between the sections of said impeller and said runners.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In an hydraulic drive, a casing for containing fluid, a drive shaft extending into one end of said casing, a driven shaft extending into the other end of said casing, a pair of spaced-apart forward and reverse driving runners in said casing rotatable about the axes of said drive and driven shafts, respectively, a duplex impeller splined on said drive shaft intermediate said runners and laterally shiftable from an intermediate neutral position in opposite directions into cooperative relation to said runners selectively to establish a fluid clutch between the same and the selected runner, means to cause said pair of runners to drive said driven shaft in forward and reverse directions, respectively, when such clutching relation is established, and means to selectively shift said impeller, the first-mentioned means comprising a cage-like cylindrical rotor rotatable about said drive shaft and inclosing said runners and said impellers, a direct driving connection between the forward driving runner and said rotor, and reverse driving connections between the reverse driving runner and said rotor.

2. In an hydraulic drive, a casing for containing fluid, a drive shaft extending into one end of said casing, a driven shaft extending into the other end of said casing, a pair of spaced-apart forward and reverse driving runners in said casing rotatable about the axes of said drive and driven shafts, respectively, a duplex impeller splined on said drive shaft intermediate said runners and laterally shiftable from an intermediate neutral position in opposite directions into cooperative relation to said runners selectively to establish a fluid clutch between the same and the selected runner, means to cause said pair of runners to drive said driven shaft in forward and reverse directions, respectively, when such clutching relation is established, and means to selectively shift said impeller, the first-mentioned means comprising a cage-like cylindrical rotor rotatable about said drive shaft and inclosing said runners and said impellers, a direct driving connection between the forward driving runner and said rotor, and reverse driving connections be-

tween the reverse driving runner and said rotor, said direct connections being yieldable and said forward driving runner being movable laterally of the impeller to permit variable spacing of said forward driving runner under variations in load on the driven shaft and variations in slippage between the impeller and said forward driving runner.

- 10 3. In an hydraulic drive, a casing for containing fluid, a drive shaft extending into one end of said casing, a driven shaft extending into the other end of said casing, a pair of spaced-apart forward and reverse driving runners in said casing rotatable about the axes of said drive and driven shafts, respectively, a duplex impeller splined on said drive shaft intermediate said runners and laterally shiftable from an intermediate neutral position in opposite directions into cooperative relation to said runners selectively to establish a fluid clutch between the same and the selected runner, means to cause said pair of runners to drive said driven shaft in forward and reverse directions, respectively, when such clutching relation is established, and means to selectively shift said impeller, the first-mentioned means comprising a cage-like cylindrical rotor rotatable about said drive shaft and inclosing said runners and said impellers, a direct driving connection between the forward driving runner and said rotor permitting yielding of said runner laterally, and reverse driving connections between the reverse driving runner and said rotor.
